W. E. GRAY.
MOUNTING MEANS,
APPLICATION FILED JUNE 11, 1918.
Patented Mar. 22, 1921.
1,372,070.

FIG. 1.

FIG. 2.

INVENTOR
WM. E. GRAY
BY J. O. Richey
HIS ATTORNEY

UNITED STATES PATENT OFFICE.

WILLIAM E. GRAY, OF ELYRIA, OHIO, ASSIGNOR TO THE ELYRIA ENAMELED PRODUCTS COMPANY, OF ELYRIA, OHIO, A CORPORATION OF OHIO.

MOUNTING MEANS.

1,372,070.

Specification of Letters Patent. Patented Mar. 22, 1921.

Application filed June 11, 1918. Serial No. 239,394.

To all whom it may concern:

Be it known that I, WILLIAM E. GRAY, a citizen of the United States, residing at Elyria, in the county of Lorain and State of Ohio, have invented certain new and useful Improvements in Mounting Means; and I do hereby declare the following to be a full, clear, and exact description of the invention, such as will enable others skilled in the art to which it appertains to make and use the same.

My invention relates to improvements in means for mounting devices in an opening in a vessel or the like.

The objects of my invention and the invention itself will be explained in connection with a description of an embodiment of the invention.

Figure 1 is a sectional view showing my invention mounted in an opening in the walls of a tank.

Fig. 2 is a section along the line 2—2 in Fig. 1.

Referring now to the drawing and to the embodiment of the invention shown therein, at 3 is shown the wall of a vessel provided with an opening 4 and a flange 5 about the opening. In the embodiment shown the opening 4 is circular and the flange 5 is integral with the vessel wall and is turned outwardly therefrom. The wall of the vessel is curved at the junction of the flange in the vessel, as shown at 6.

A jacket 7 may be mounted about the wall of the vessel, provided with an opening 8, preferably of the same shape as the opening 4 and in alinement therewith. The mounting means proper is shown at 9 and consists of a member adapted to extend through the openings 4 and 8. In the embodiment shown the transverse section of the member 8 is circular. The member 9 is provided with a bore 10 through which there extends an agitator shaft 11. The member 9 is provided with a second opening 12, through which there extends a part 13 of a thermometer. The part 9 is provided with a chamber 14, which serves to house a portion of a thermometer.

In the embodiment shown the walls of the opening 12 are threaded, as shown at 15 and the thermometer is provided with a portion 16 having threads 17 to coöperate with the threads 15. In the embodiment

shown the thermometer is provided with a second portion 19, including a scale to indicate the temperature within the vessel. The part 13 may, as here shown, extend through the mouth 20 of the chamber into the vessel. An agitator 21 is mounted on the shaft inside the vessel and suitable means, such as a pulley 22, is employed for rotating the propeller. In the embodiment shown, the member 9 is provided with a collar 23, the rear portion of which is threaded, as shown at 24, to coöperate with the threads on a lock nut 25. The forward end of the member 9 is provided, in the embodiment shown, with a flange 26, adapted to serve as an abutment for a ring 27, which engages the interior of the flange 5. The flange 26 may engage the curved portion 6 of the collar 5, at the points 30, assisting in preventing the accidental removal of the member 9 from the opening.

Where a jacket is used, suitable means are employed for connecting the member 9 to the jacket. In the embodiment shown, rings 40 and 41 are employed for this purpose. The ring 40 is provided with a main portion 42, which extends through the opening 8, and with a flange 43, which engages the inside of the wall 7. The ring 41 is provided with an extension 44, which acts through packing material 45 against the jacket 7. Suitable means are provided for connecting these parts together, such as bolts 48. Packing 50 is used at various places to tightly seal the joints.

The shaft is provided with a conical thrust bearing 60, adapted to engage with a bearing 61 on the front end of the member 9.

It will be understood that any suitable form of agitating means or thermometer may be employed in connection with the embodiment of my invention illustrated in the drawing.

It will be seen that I have used mounting means common to both the thermometer and the agitating mechanism for mounting both these devices in the same opening in a vessel wall. I have thus produced a unitary structure which can be removed, transported and remounted as a whole, from one tank to another. It will also be seen that by the use of my invention the means for making observation upon and agitating the contents

of a vessel may be readily installed upon any vessel and that to do so, where my invention is used, it is necessary to make only one opening therein.

5 I have shown this particular embodiment of my invention and the details thereof for the purpose of better describing the same. It will be apparent to those skilled in the art that numerous and extensive departures 10 may be made from both the embodiment shown and the details thereof, without departing from the spirit of the invention.

I claim:

1. In combination, a vessel, a jacket for 15 the vessel, a plug piercing the vessel and the jacket, said plug serving as a hub for a packing joint for the vessel and for a packing joint for the jacket, said plug having a solid section throughout its entire thickness, with a shaft bearing extending 20 through said solid section, a chamber recessed in the plug to one side of the bearing and terminating in a head, and a thermometer projecting through the head and 25 into the chamber and beyond into the vessel.

2. In combination, a shaft bearing, a chamber mounted on one side of said bearing having a head located approximately near the center along the length of the bearing, a thermometer mounted in said head and extending along the length of the chamber, said bearing projecting through the 30 walls of two chambers, and a packing joint on said plug for each chamber, one of said 35 chambers located within the other.

3. In combination, a vessel and a jacket for the vessel, an opening in each, said openings located in juxtaposition, a plug extending through both openings and 40 mounted on the vessel and on the jacket, a shaft bearing extending through said plug and a shaft extending therethrough, a recess in said plug extending from the inner vessel outwardly and beyond the jacket 45 and terminating in a wall, and a ther-

momter piercing said wall and extending through the length of the recess.

4. In combination, a shaft bearing, a chamber mounted on one side of said bearing having a head located approximately 50 near the center along the length of the bearing, a thermometer mounted in said head and extending along the length of the chamber, said bearing projecting through the walls of two chambers, a packing joint on 55 said plug for each chamber, one of said chambers located within the other, threads on the outside of said plug, and a packing nut engaging said threads, said packing nut serving to control the packing in one of said 60 joints.

5. In combination, a cylinder, a plug therefor, said plug consisting of a long tube serving as a shaft bearing and of a short tube within which the long tube is located, 65 the inner ends of both tubes being flush, a shaft in said bearing, the shorter tube having a head along the head of the longer tube, and a thermometer in said head and projecting into the shorter tube and extending 70 toward the flush ends of the tubes.

6. In combination, a cylinder, a plug therefor, said plug consisting of a long tube serving as a shaft bearing and of a short tube within which the long tube is located, 75 the inner ends of both tubes being flush, a shaft in said bearing, the shorter tube having a head along the head of the longer tube, and a thermometer in said head and projecting into the shorter tube and extending 80 toward the flush ends of the tubes, said shaft serving to operate a propeller to mix a fluid in the tank and the thermometer serving to register the temperature of the fluid.

In witness whereof, I have signed my name at Elyria, in the county of Lorain and State of Ohio, this 3d day of June, 1918.

WILLIAM E. GRAY.
